FIG. 2.

UNITED STATES PATENT OFFICE.

GEORGE W. FISHERING, OF ALLEGHENY, PENNSYLVANIA.

SPRING BED-BOTTOM.

SPECIFICATION forming part of Letters Patent No. 275,476, dated April 10, 1883.

Application filed September 13, 1882. (No model.)

To all whom it may concern:

Be it known that I, GEORGE W. FISHERING, a citizen of the United States, residing at Allegheny, in the county of Allegheny and State of Pennsylvania, have invented a new and useful Improvement in Spring Bed-Bottoms, of which the following is a specification.

My invention relates to an improvement in spring bed-bottoms, and relates particularly to those bed-bottoms in which are used double conical spiral springs, and is designed to obviate the necessity of any hook arrangement to connect said springs.

In the accompanying drawings, Figure 1 is a plan view, looking at the top, of a spring bed-bottom, showing my invention. Fig. 2 is a perspective view of a small section containing two spirals.

Similar letters refer to similar parts throughout the different views.

The slats A, secured to the end blocks, B, constitute the bed-frame, to which the springs are secured. The springs a of the double spring C are inserted in and stapled to the slats A at the point s. Then the springs b are pressed through the space e of the adjacent spring, so as to interlock the top spire of the spring a with the top spire of the spring b at the point x. The ends of the wire which forms

the springs b are inserted in and secured to the slats A at a point distant from the point of insertion s of the spring a equal to the distance across the top or largest spire of said springs. In a like manner the springs c and d are pressed through the space e of the adjacent spring, so as to interlock, and secured to the slats at equal distances apart, and so on with as many springs as are required to fill the bed-frame. To give rigidity to the springs lengthwise over the bed, the ends of each series of springs are connected with the end blocks, B, by means of a chain or wire, f, interlocking with the said springs, and firmly stapled to top of the end blocks, B.

Having thus described my invention, what I desire to claim and secure by Letters Patent is—

In a spring bed-bottom, the combination of two or more double conical spiral springs, having the largest or top spire of each spring that forms the pair interlocked with the largest spire of each adjacent spring that forms a similar double spring, substantially as described, and for the purpose specified.

GEORGE W. FISHERING.
